LUCIUS COLBY, OF MORRISSVILLE, VERMONT, AND JOHN D. GILMAN, OF BOSTON, MASSACHUSETTS.

Letters Patent No. 85,908, dated January 19, 1869.

IMPROVED CARPET-STRETCHER, TACK-DRIVER, AND PULLER COMBINED.

The Schedule referred to in these Letters Patent and making part of the same.

To all whom it may concern:

Be it known that we, LUCIUS COLBY, of Morristown, county of Lamoille, State of Vermont, and JOHN D. GILMAN, of Boston, county of Suffolk, State of Massachusetts, have invented an Improved Carpet-Stretcher, Tack-Driver, and Tack-Puller Combined; and we do hereby declare that the following is a full, clear, and exact description thereof, reference being had to the accompanying drawings, making part of this specification, in which—

Figure 1 represents a perspective view of our invention complete.

The object of our invention is to produce a carpet-stretcher, tack-driver, and tack-puller combined, which shall be at once convenient for use, cheap, and durable.

Our invention consists in having the hammer, stretcher, and puller in two pieces or arms, with a spring, the hammer operating over the stretcher.

In the drawings—

A is a suitable-sized plate, of metal, provided with teeth *h* and slot *p*. This plate and teeth form the stretcher-part of our invention.

B is a shank to plate A.

To this shank is attached handle H.

K is a bar attached to B at *l* by means of arm E and pin *i*. This bar K works parallel to B.

At one end of K, over plate A, is attached hammer-head C.

A spring, S, is attached to shank B at *m*, and bears upon arm K at *b*.

At the front of plate A is cut slot *p*.

Shoulder *a*, on one end of hammer-head C, plays within slot *p*.

To one side of plate A is attached claw L for drawing tacks.

The operation of our invention is as follows:

A tack is easily and conveniently picked up by end *f* of the hammer C, by the hammer being magnetized for this purpose. The tack can then be inserted, by a slight blow, into the edge of a carpet, and the instrument turned over, then stretching the carpet as desired by plate A and teeth *h*; taking care to have the tack

come within slot *p*, and of course the tack is then directly under hammer C. Now, while the hand holds H, and the carpet is being crowded to its place, the end of bar K is pressed down by pressure at D, and the pressure being suddenly withdrawn, the strength of spring S causes hammer C to come down with sufficient force upon the tack to drive it home; or partly, as the blows can be repeated till the tack is driven home.

Or, the tack can be easily handled with the disengaged hand of the operator, and conveniently attached to the hammer by this disengaged hand, and the tack is held to the lower face of the hammer by magnetic force, and when the carpet is in the right place, the other hand lifts the hammer, by pressure at D with the thumb, and withdrawing the pressure, the action of the spring S drives the tack home.

This combination has another advantage, that of having a claw, L, ready to draw a tack, if desired.

We are aware that combined carpet-stretchers and tack-drivers have been made and used, but not constructed as we construct this. We are not aware of any combined carpet-stretcher, tack-driver, and tack puller.

We disclaim the hammer operated by a combination of levers, and disclaim the arm when an additional hammer detached from the stretcher is required; but

What we do claim, is—

The combination of plate A, arranged as a puller and stretcher, with the arm K pivoted at *i*, and furnished with the hammer C at one end, and held by the spring S at the other, substantially as and for the purposes set forth.

In testimony whereof, we have signed our names to this specification, in the presence of two subscribing witnesses.

LUCIUS COLBY.
JOHN D. GILMAN.
